ELECTROMETER OR SIMILAR ARTICLE

Charles M. Dole, Jr., 288 Lexington Ave., New York,
N.Y., and Robert S. Quandt, 41 Red Berry Road,
Levittown, Pa.

Filed July 7, 1964, Ser. No. 30,739

Term of patent 14 years

(Cl. D26—1)

FIG. 1

FIG. 2

FIG. 3

FIG. 4

FIG. 5

FIG. 1 is a perspective view of the front and side of an electrometer or similar article, showing our new design;

FIG. 2 is a front elevation view;

FIG. 3 is a back elevation view;

FIG. 4 is one side elevation view; and

FIG. 5 is the other side elevation view thereof.

A portion of the drawing is diagonally lined to indicate transparency.

We claim:

The ornamental design for an electrometer or similar article, substantially as shown and described.
